CLAIM

The ornamental design for a nail gun body, as shown and described.

DESCRIPTION

FIG. 1 is a perspective view of a nail gun body showing the new design;

FIG. 2 is a front view thereof;

FIG. 3 is a rear view thereof;

FIG. 4 is a left side elevational view thereof;

FIG. 5 is a right side elevational view thereof;

FIG. 6 is a top view thereof; and

FIG. 7 is a bottom view thereof.

FIG. 8 is a right side elevational view showing the nail gun body in condition of use with a broken line, first nail magazine.

FIG. 9 is a perspective view showing the nail gun body in condition of use with the broken line, first nail magazine.

FIG. 10 is a right side elevational view showing the nail gun body in condition of use with a broken line, second nail magazine.

FIG. 11 is a right side elevational view showing the nail gun body in condition of use with a broken line, third nail magazine.

FIG. 12 is a right side elevational view showing the nail gun body in condition of use with a broken line, fourth nail magazine.

FIG. 13 is a right side elevational view showing the nail gun body in condition of use with a broken line, fifth nail magazine; and,

FIG. 14 is a right side elevational view of another preferred embodiment of the nail gun body.

The broken line showing of environmental structure, in the form of nail magazines in FIGS. 8 through 13, is for illustrative purposes only and forms no part of the claimed design.
